Nelson W. Howard

UNITED STATES PATENT OFFICE

JOSEPH V. REED, OF NEW YORK, N. Y., ASSIGNOR, BY MESNE ASSIGNMENTS, TO UNITED SHOE MACHINERY CORPORATION, OF PATERSON, NEW JERSEY, A CORPORATION OF NEW JERSEY

LAST FOR TURN SHOES

Application filed June 22, 1928. Serial No. 287,411.

This invention relates to shoe lasts and in particular to lasts for use in relasting turn shoes.

The second lasting operation on turn shoes, that is, the insertion of the last after the shoe is turned, is attended with some difficulty, in that the upper and lining have to be stretched to a considerable degree to shape them after turning and the last has therefore to be forced into the shoe under considerable pressure. It is the common practice to put the last into the shoe as far as possible and then to hold the shoe in the hand by its waist portion and to hammer the upper part of the heel end of the last on the bench in order to force the last completely into the shoe and to permit drawing the counter portion of the shoe up over the heel of the last.

20 The upper part of the heel end of a woman's last is rather thin, and this practice damages many lasts, crushing and splintering the portion mentioned.

It is an object of the present invention to 25 provide a last for turn shoe making which shall obviate, among others, the above described disadvantages. Accordingly, I have provided a last having a piece of material, considerably harder than the wood of which 30 the main body of the last is made, inserted in the upper part of the heel end of the last, and extending a substantial distance from the upper end of the heel toward the tread surface of the heel. To secure economy this 35 reinforcing piece is preferably distinct from the reinforcement used along the flat cone-top of the last to protect the last from damage in the heeling machine. The illustrated last is also provided with the customary 40 channel or hole for the heel attaching screw, located back of the thimble.

These and other features of the invention will be better understood from the following description of a preferred embodiment 45 shown in the drawing which shows a side elevation of a last, partly in section.

The last shown is a block last and comprises a main body 10 with a detachable block 12, as will be well understood. The 50 main body is provided with a jack pin thim-

ble 14, and the upper surface of the cone may be reinforced at 16 with a strip of fiber or leather or any of the well-known combinations of strips of the two.

The upper rear end of the last is recessed 55 as shown at 18. The recess extends a considerable distance down the rear end of the last, preferably one third or more of the height of the heel end. This recess is preferably formed by a transverse vertical and 60 a horizontal longitudinal cut as shown. The horizontal cut is, in the last shown, at an acute angle to the vertical cut to assist in preventing displacement of the filler piece which is to be inserted in the recess thus 65 formed. In the illustrated last the height of the recess is about two thirds of the height of the heel end. The depth of the recess, as shown, is about $\frac{1}{4}$ inch at the top and $\frac{1}{2}$ inch at the bottom. The contour of the heel 70 end of the last is filled out with a filler piece or insert 20, which is fastened to the main body of the last in any convenient way such as by dowels 22, 22. Any suitable material, more resistant to blows than the wood of 75 which the last is made, may be used for the insert 20. I have found fiber cheap and very desirable. The reinforcing strip 16 abuts against the upper end of the insert 20.

The illustrated last is also provided with 80 a heel attaching screw hole 24 reinforced at its upper end by a metallic thimble 26 to avoid wear and crushing-in of the sides of the hole under the pounding experienced by the last.

The last is used in exactly the same way 85 as above described, the fiber insert 20 taking the violent blows necessary to force the last into the turned shoe, without damage to the last.

Having thus described my invention, what I claim as new and desire to secure by Letters Patent of the United States is:

1. A wooden last having in its rear end a 90 recess beginning at a point in the upper surface of the cone and running directly from the upper surface of the cone toward the bottom and having a filler piece of harder material than wood in the recess shaped to the 95 normal heel contour of the last.

2. A wooden last having in its rear end a substantially vertical recess with an acute angled lower end extending from the top of the cone toward the bottom a distance of more than one third the height of the rear end of the last, and having a piece of fiber rigidly fastened in the recess and shaped to the normal heel contour of the last.
3. A wooden last having a heel attaching-screw hole extending downwardly and forwardly from the rear end of the top of the cone to the bottom of the heel end, a reinforcing metal thimble in the upper end of the said hole, the last having also a substantially vertical recess in the heel end to the rear of the said hole and thimble, formed by a transverse vertical cut extending from the upper surface of the cone downwardly to a point less than two thirds the height of the heel end from the bottom of the heel end and by a longitudinal horizontal cut extending from the rear end surface of the last to the bottom of the first-mentioned cut and at an acute angle thereto, and a filler piece of fiber fastened rigidly in the recess and shaped to the normal contour of the last heel end.
4. A wooden last having a fiber insert at the upper part of its rear end, extending downwardly from the top of the cone over a substantial portion of the rear end of the last, the last having also a reinforcing plate attached to the upper surface of the cone and abutting the said insert at its rear end.
- 35 In testimony whereof I have signed my name to this specification.

JOSEPH V. REED.
